his ATTORNEY

UNITED STATES PATENT OFFICE

FRANK C. LA MAR, OF PITTSBURGH, PENNSYLVANIA, ASSIGNOR TO GREAT WESTERN FUSE COMPANY, OF PITTSBURGH, PENNSYLVANIA, A CORPORATION OF DELAWARE

RENEWABLE ELECTRIC FUSE

Application filed January 5, 1927. Serial No. 159,079.

More particularly my invention relates to ferrule-type fuses.

In electric fuses when the fusible element or "reload" is fused or burns out gases are generated in considerable volume and at high temperatures and such gases carry in suspension particles of the fused metal.

A fault of the types of renewable fuses now in common use is the tendency toward a concentrated escape of the gases axially of the fuse, frequently resulting in welding the parts of the mechanism together either by fusion or by the deposit of the metallic particles. Thus the cap may be fixed to the ferrule or the anchoring disk may be fixed to either or both, so as to be removable, if at all, after a great deal of trouble or the extremity of the fusible element may be welded to the anchoring disk or ferrule to both.

Escape of the gases formed by fusion of the fusible element must, of course, be provided for to prevent rupture of the fuse which would prevent its reuse, but a concentrated escape must be avoided to prevent the objectionable occurrences above mentioned.

My object therefore is to so improve the construction of renewable ferrule fuses that a restricted and widely distributed escape is provided for the gases and the material deposit of the metal particles on the parts in movable relation is avoided.

Thus I provide means whereby a restricted escape for a portion of the gases is provided around the perimeter of the washer which anchors the end of the fusible element and between the cap and the ferrule.

I also provide means for baffling a portion of the gases before they leave the ferrule to cause the deposit of the metallic particles before they reach the parts in movable relation.

Other novel features of construction, and also of arrangement of parts, will appear from the following description.

In the accompanying drawings, wherein I have illustrated the best embodiment of the principles of my invention now known to me, Fig. 1 is an elevation of a renewable ferrule fuse partially broken away in longitudinal section to show the internal parts; Fig. 2 is a similar view but turned ninety degrees

from Fig. 1; Fig. 3 is an enlarged diametric section of one of the ferrules, its anchoring disk and cap, the ferrule being slightly modified in construction from that shown in Figs. 1 and 2; Fig. 4 is a perspective of the anchoring disk; Fig. 5 is a view similar to Fig. 3 but showing a modification wherein the baffle is a separate element from the ferrule, and Fig. 6 is an elevation of the baffle shown in Fig. 5.

Referring first to Figs. 1 and 2, 1 represents the usual cylindrical shell of insulating material, such as fibre and within which the fusible element or reload 2 is contained. On each end of the shell 1 is fixed a metal, usually brass, ferrule 3. The ends of the shell 2 are preferably provided with notches 2a to prevent a sealing contact between the end of the shell and the ferrule. The inner end of the ferrule is provided with internal threads which screw onto the external threads of the end of the shell 1. The outer end of the ferrule 3 is of reduced external diameter, thus forming an intermediate circumferential shoulder 4.

The outer end of the ferrule is provided with exterior threads 5 upon which are screwed the interior threads 6 of the metal cap 7 which is preferably also of brass. At either end of the threaded portion 5 of the ferrule 3 is a plane annular surface of the depth of the threads, which surfaces form with the skirt of the cap 7 annular chambers 8 at the extremities of the threaded engagement between the cap and the ferrule.

The end of the cap is closed thus preventing direct axial escape of gases.

The ferrule 3 is provided with an internal annular shoulder 9 at the end of the shell 1 defining a central opening or throat 10 which provides clearance for the fusible element 2. The shoulder extends inwardly from the edge of the sleeve to form a baffle. In Figs. 1 and 2 said shoulder or baffle 9 is disposed in a plane at right angles to the axis of the shell and ferrule, while in Fig. 3 said shoulder or baffle is frusto-conical in shape extending inwardly of the shell 1.

The bore of the ferrule outwardly from the shoulder is of progressively increasing diameter for the double purpose of giving

clearance for the angularity of the fusible element 2 and to better distribute the gases which may pass outwardly through the throat 10.

5 At the outer end the bore of the ferrule 3 is countersunk to form a disk-seat whose inner end is the annular shoulder 11 and its side the annular wall 12.

10 13 is the disk which is employed to anchor the end of the fusible element 2, the disk being provided with an eccentrically positioned slot 14 through which the extremity of the fusible element is inserted, said extremity being then bent down flat against the 15 exterior surface of the disk, as shown. In assembling the fuse, the disks are positioned with their slots disposed at opposite sides of the axial line of the fuse, thus causing the angularity in the disposal of the fusible element shown in the drawings.

20 The disk 13 is of proper diameter to fit loosely in its seat and is set outwardly in the same by means of its struck-out toes 15 which rest on the shoulder 11. Thus there is provided a restricted escape for the gases around the perimeter of the disk 13 and between it and the ferrule.

25 The disk preferably protrudes slightly from the end of the ferrule and when the cap 30 7 is screwed into place, it clamps the bent-over extremity of the fusible element between it and the disk and also clamps the disk to the ferrule. The end of the cap 7 is spaced away from the end of the ferrule. 35 The skirt of the cap 7 is short enough to insure a space between it and the ferrule shoulder 4.

40 It is evident that in case of a burning-out or fusing of the fusible element, the formed gases will be in part baffled by the shoulder 9, which baffling action will be accentuated by the frusto-conical form of baffle shown in Fig. 3, thereby causing a deposit of a material portion of the metal particles carried 45 by the gases and preventing such particles being deposited on or between the ferrule, the disk and the cap. Furthermore a portion of the gases will be trapped by said baffle and will be diverted and caused to find a restricted escape between the threads of the 50 shell and the ferrule.

55 The remainder of the gases, passing outwardly through the throat 10 will find a distributed escape around the perimeter of the disk 13 and will then escape through the chambers 8 and between the ferrule 3 and the skirt of the cap 7 between the threads of the same.

60 It is thus evident that there can be no concentrated escape of the gases in such volume as to weld together parts in movable relation nor to cause danger of fire. At the same time sufficient of the metal particles are diverted from passing through the throat 10 65 to prevent such welding action through the

deposit of such particles. Again, the escape of the gases is so fully provided for that no rupturing of the fuse is possible.

In Figs. 5 and 6 I show the baffle formed as a separate element 16 formed with a perimetral lip 17 which is clamped between the end of the shell 1 and an internal shoulder 18 of the ferrule, while the body of the element is of frusto-conical form extending inwardly of the shell 1. In this case the outer bore of the ferrule may be cylindrical instead of conical.

This modified form is less expensive than that shown in the preceding views of the drawings, and thus may be regarded as preferable.

What I desire to claim is:—

1. In a renewable electric fuse, the combination of a shell of insulating material, a ferrule mounted on the end of the shell, an anchoring disk bearing against the end of the ferrule, the disk being spaced from the end of the ferrule to provide for the escape of gases between the ferrule and the disk, a fusible element in the shell and having its end anchored to the disk, and a cap screwed onto the ferrule and holding the disk in position.

2. In a renewable electric fuse, the combination of a shell of insulating material, a ferrule mounted on the end of the shell, the bore of the ferrule being provided with a seat at its outer end, a disk mounted in said seat, means for spacing the body of the disk out of contact with the ferrule to provide for the escape of gases around the disk, a fusible element in the shell and anchored to the disk, and a cap screwed onto the ferrule and holding the disk in position.

3. In a renewable electric fuse, the combination of a shell of insulating material, a ferrule permanently mounted on the end of the shell and provided with an exteriorly threaded portion, an anchoring disk bearing against the outer end of the ferrule, the ferrule having an inwardly contracting central opening through which the fusible element extends, a fusible element in the shell having its end anchored to the disk, and a threaded cap screwed onto the threaded portion of the ferrule, and means for diverting a portion of the gases of fusion to escape between the portions of the ferrule and the cap which are in threaded engagement.

4. In a renewable electric fuse, the combination of a shell of insulating material, a ferrule permanently mounted on the end of the shell and provided with an exteriorly threaded portion, an anchoring disk bearing against the outer end of the ferrule, the ferrule having an inwardly contracting central opening through which the fusible element extends, a fusible element in the shell having its end anchored to the disk, and a threaded cap screwed onto the threaded portion of the fer-

rule, and a baffle in said ferrule arranged to divert a portion of the gases of fusion and cause them to escape between the portions of the ferrule and the cap which are in threaded engagement.

5 Signed at Tucson, Arizona, this 24th day of December, 1926.
